UNITED STATES PATENT OFFICE.

JOHN J. RONDERS, OF MONONGAH, WEST VIRGINIA.

SWITCH POINT.

Original application filed October 26, 1922, Serial No. 597,016, now Patent No. 1,463,227, dated July 31, 1923. Divided and this application filed March 30, 1923. Serial No. 628,853.

To all whom it may concern:

Be it known that I, JOHN J. RONDERS, a citizen of the United States, residing at Monongah, in the county of Marion and State of West Virginia, have invented certain new and useful Improvements in Switch Points, of which the following is a specification.

This invention relates to improvements in railway switches and the primary object of the invention is to provide a railway switch in which the parts will be so constructed and arranged and adapted for operation in such manner as to insure against wrecks such as are liable to result from displacement of the switch points.

Another object of the invention is to provide a novel form of switch point and a novel means for actuating the same, the point being so constructed and mounted and operated in such a manner as to insure against accidents through its disarrangement from any cause, such for example, as the dropping and dragging of a brake shoe or other parts of a car passing over the switch.

In the accompanying drawings:

Figure 1 is a plan view of the switch embodying the invention, the switch point being adjusted to position to provide for travel over the main track;

Figure 2 is a vertical transverse sectional view taken substantially on the line 2—2 of Figure 1 looking in the direction indicated by the arrows, the view illustrating the switch point in position for travel of the train over the main track;

Figure 3 is a similar view illustrating the point in position for travel of the train over the side track;

Figure 4 is a sectional perspective view illustrating one of the switch points, the actuating means therefor, and the main track rail with which it coacts;

Figure 5 is a view similar to Figure 2 illustrating a modification of the invention.

The present application is a division of my co-pending application filed October 26, 1922, Serial No. 597,016, now Patent Number 1,463,227 granted July 31, 1923, and relates more particularly to a switch point whereas the said co-pending application relates to a frog structure which is illustrated in the drawings, of the present application, by the reference letter F.

In the drawings the main track rails are indicated, one by the numeral 1 and the other by the numeral 2, and the siding rails one by the numeral 3 and the other by the numeral 4, the rails being mounted upon the usual ties 5.

In Figure 1 and the associated figures, the switch point is indicated in general by the numeral 9, and the same may, if desired, be formed from a length of ordinary rail or it may be initially formed of the required shape from other stock material. In any event the point will comprise a head 10 corresponding in general form to a section of an ordinary rail head, a web 11, and a base flange 12. As distinguished from the ordinary switch point which is swiveled at its butt-end to the main or siding rail, as the case may be, and is adapted to be swung toward and away from the companion rail, the point embodying the invention is hinged at one edge of its base flange as at 13, to the ties or any other base structure which it may be found advisable to employ, and the point is adapted to be moved upon its hinges so as to occupy a position resting against the side of the rail or a position tilted away from the rail to permit of passage of the wheel flanges.

In order that a smooth and unobstructed surface may be provided at the treads or heads of the rails where the switch point meets the companion rail, the said companion rail preferably has one side of its head formed with a shallow recess 14 into which the tongue of the point is adapted to seat when the point is swung up to position beside the rail. This recess is as stated shallow so that even when the point is away from the rail, the wheel flanges

may pass the recess without any battering of the rail or injury to the wheels. At the same time, when the tongue of the point is seated in the recess, the outer or guiding side of the head of the point will be flush and even with the corresponding side of the head of the rail and there will be no likelihood of damage to the point when the wheels pass over the same.

In the form of the invention shown most clearly in Figures 1 to 4, inclusive, of the drawings, the operating means for the switch comprises a bar 15 which is pivoted at one end as at 16 to the under side of a plate 17 secured upon the ties 5, the bar extending between two

adjacent ones of the ties and beneath the rails and the switch points associated therewith. The main flange of each rail is cut away at a suitable point as indicated by 5 the numeral 18, this cut away portion being in the side of the flange next adjacent the switch point, and the bar 15 is formed with an overhanging lip 19 which is adapted to ride over the upper side of the main flange 10 of the rail in the movement of the bar 15 about its pivot. The bar 15 is also provided with a similar lip 20 which engages over the base flange 12 of the switch point 9. Also the bar is formed between the lips 19 15 and 20 with an upstanding tongue 21, the upper end of which may be slightly deflected laterally toward the lip 20 as indicated by the numeral 22, to ride against the inner side of the web 11 of the switch point 9. 20 Of course, the bar 15 will be provided with two sets of the elements 19, 20 and 21 for coaction with the two switch points which extend above the bar. The tongue 21 is accommodated within the cut out portion 25 18 of the base flange of the rail with which the respective switch point coacts, and it will be understood that when the bar is swung about its pivot in either direction, one of the lips 20 thereon will ride against 30 the respective switch point and swing the same about its hinges to upright position against the companion rail as shown clearly at the left of Figure 2 of the drawings, the tongue 21 associated with the other switch 35 point riding against the same to tilt the point about its hinges to position spaced from the companion rail as shown at the right in said Figure 2. A swinging of the bar 15 about its pivot in the opposite direction will effect a reverse operation of the two switch points as clearly shown in Figure 3.

In order that the bar 15 may be actuated, a switch stand 23 is provided and comprises a suitably mounted lever 25 having a finger 26 extending below its pivot and working through an eye 27 swiveled to the end of the bar 15.

In that form of the invention shown in 50 Figure 5 of the drawings, the switch points which are indicated by the numeral 28 are hinged at their base flanges as indicated

by the numeral 29, and a bar 30 is slidably mounted beneath the rails and switch points in suitable guides 31, and is provided with 55 upstanding arms 32 pivotally connected as at 33, to the said switch points. An operating lever 34 is pivotally mounted as at 35 and provided with an arm 36 which works through one end of the bar 30, and it will 60 be evident by reference to the said figure that when the lever is rocked in one direction, one switch point will be thrown to position beside its respective rail and the other point away from its respective rail, 65 and when the lever is swung in the opposite direction, the position of the switch points will be reversed.

Having thus described the invention, what is claimed as new is:

1. In a railway switch, the combination with main and siding rails, of a switch point substantially in alinement with one of said rails, means supporting the said point and hingedly mounting the same at its base for 70 tilting movement toward and away from the other rail, and means for tilting the point comprising a pivoted bar, means for moving the bar about its pivot, and means upon the bar coacting with the opposite sides of the point for tilting the point toward the said other rail when the bar is swung in one direction and tilting the point towards the said other rail when the bar is swung in the opposite direction.

2. In a railway switch, the combination with main and side track rails, of a switch point substantially in alinement with one of said rails and mounted at its base for 75 tilting movement toward and from the other rail, a bar pivoted at one end and extending transversely beneath the said rails and point, means for swinging the bar about its pivot, lips upon the bar slidably engaging the base flanges of one of said rails and the said point, and a tongue upstanding from the bar between the said lips and between the said switch point and the associated rail and having an outturned end for coaction 80 with the web of the said switch point.

In testimony whereof I affix my signature.

JOHN J. RONDER. [L.S.]
